PERMUTATION LOCK

Filed Nov. 7, 1927

Inventor:
Joseph Feltmeyer
Attorney.

UNITED STATES PATENT OFFICE

JOSEF FELDMAYER, OF MUNICH, GERMANY

PERMUTATION LOCK

Application filed November 7, 1927, Serial No. 231,647, and in Germany July 29, 1927.

This invention relates to a permutation-lock adapted to be used for trunks, portfolios, cupboards, doors and padlocks, and which is characterized in that the adjusting elements need not be adjusted on certain marks, as is the case in most types of permutation-locks of known construction. An essential feature of the invention is, that any number of loose locking bodies are provided, which intersect the path along which the spring bolt is moved and which must be adjusted to a predetermined position, when the lock has to be unlocked. These locking bodies are all of the same outer shape and each of these locking bodies can be oscillated by means of a handle into three different positions, in which said locking elements are securely held by springs.

When any of the locking bodies is in the wrong position it is impossible to unlock the lock. The locking bodies are of such simple construction and of such small size that a great number of the same can be arranged in a small space. When ten locking bodies, each being adapted to be adjusted to three different positions, are provided, 3¹⁰ or 59049 adjusting are possible, of which only one is the correct position. The number of required adjusting may be determined by the owner of the lock. By leaving a certain number of locking bodies permanently in the correct position, only a few locking bodies—or—only one single locking body has to be adjusted. A slight difference in the construction of the locking bodies, which is however not visible from the outer side, makes it necessary to give to these locking bodies, when adjusted into the unlocking position, another position than for the normal position of the other locking bodies, so that by these special locking bodies the lock can be locked already when they are being brought into the same position as the other locking bodies, this position being for these other locking bodies the unlocking position. It is then impossible to see from the outer side which locking body has to be adjusted. Either all locking bodies will have to be adjusted or only one or several of these locking

bodies in a succession which only the owner knows.

Another essential feature of the invention is that the locking bodies are loosely inserted and covered and held in their bearings by means of a comb shaped retaining plate which, when the lock is opened, can be pulled out so that all locking bodies are accessible and can be interchanged at will. The owner of the lock must of course remember at which points the abnormal locking bodies have been inserted. After the re-insertion of the comb shaped retaining plate after all the locking bodies have been inserted and arranged for the desired permutation-lock-action, the lock, with its changed combination, is ready for use.

A permutation-lock, according to the invention is shown, by way of example, in the accompanying drawing in which

Fig. 1 shows a longitudinal section on line I—I of Fig. 2, and Fig. 2 is a top-plan-view.

Fig. 3 is a cross-section on line III—III of Fig. 2.

Figs. 4, 5 and 6 show the locking-bodies.

In the drawing the lock is shown in the open position, the comb shaped retaining plate 10 being pulled out partly, this being done however only, when the locking bodies are to be re-grouped. The most important parts of the lock are the locking bodies or tumblers 1 and 1' shown in Figs. 4, 5 and 6. The locking body consists of a disk-shaped part and of a handle. In the disk-shaped part a short axle 2 is fixed. Each locking body has in the rim of the disk-shaped part a notch, which either stands diametrically opposite the handle, as notch 3 in Fig. 4, or at a certain angle to the diametrical line of the handle, as notch 3' in Fig. 6. The locking body shown in Fig. 4 is symmetrical or normal, that shown in Fig. 6 is unsymmetrical or abnormal. Each locking body has further two indentations 4 arranged symmetrically to the handle in either side of the disk-shaped part.

These locking bodies are inserted the one after the other into a bearing body. The bearing body 5, which is connected by rivets or is otherwise fixed to the casing, has slots

6, in the form of construction shown two rows comprising each four slots so that eight locking bodies can be inserted. The disk-shaped parts of the locking bodies 1, 1' just fit in the slots 6. The bearing body 5 has in longitudinal direction two grooves 7 of semicircular cross-section which intersect the slots 6 at the middle. When the locking bodies are being inserted, the short axles 2 of 10 the same come into engagement with said grooves 7. The bearing body 5 is fixed to the cover plate of the casing 8 at a short distance from said cover plate. Into the gap between the upper end of the bearing body 5 and the 15 inner surface of the cover plate of the casing a comb-shaped retainer plate 10 is inserted, the teeth of which engage between the locking bodies and securely hold the axles 2 of the locking bodies in the bearing grooves 7, 20 the locking bodies being thus secured against shifting in lateral directions. In the cover plate of the casing two oblong slots 11 are arranged through which the locking bodies are to be inserted. The locking bodies and 25 their bearing bodies are covered by the comb shaped retaining plate 10 so that, through the slots 11 of the cover-plate of the casing, only the comb shaped retaining plate and the handles of the locking bodies are visible 30 which project between the teeth of said comb shaped retaining plate. The handles of the locking bodies are covered by a lid 13, pivotally mounted on a pin 12, fixed in the cover-plate, a knob 14 serving to secure the lid 13 in 35 the closing position. Underneath the bearing body 5 a spring lock bolt 15 is shiftably mounted. This spring bolt 15 has two vertical ribs 16 extending in a longitudinal direction, each one accurately underneath the central lines of the corresponding row of locking bodies. These ribs 16 intersect the inserted 40 locking bodies and engage with the notches 3, 3' respectively of the same. Under the spring-bolt 15 a plate spring 17, fixed to 45 the bearing body 5 is arranged. The spring-bolt 15 is shiftable as its short slot engages over the shaft of a screw-bolt 18, screwed from below into the lock casing. The plate-spring 17 is bent in U-shape around the two 50 side walls of the bearing body 5 and the two arms 19 of the spring bear against the disk-shaped parts of the locking bodies which project from the slots 6 of the bearing body 5. The plate spring 17 is subdivided by incisions 55 20 into sections which each bear against one locking body. The ends of the arms 19 of the plate-springs are rolled in an inward direction to form a bead engaging with the corresponding indentations 4 of the locking bodies, which are thus securely held in the central position.

All the locking bodies 1 and 1' are inserted into their bearings in opposition to the action of the arms 19 of the plate-spring 17, either 60 in the central position or any other suitable

position. Each rib 16 of the spring-bolt 15 comprises a plurality of rib members separated by and alternating in arrangement with recesses 21 adapted to receive the locking bodies, the disk-shaped part of said locking bodies engaging with one of these recesses 21, when the locking bodies are being inserted. The recesses 21 are disposed accurately underneath the locking bodies, when the spring-bolt 15 is in the locking position. 75 When the spring-bolt is to be shifted into the unlocking position, its ribs 16 must pass through the notches 3, 3' of the locking bodies. This is possible only when all symmetrical locking bodies 1 are in the central position as shown in Fig. 3. When one of the locking bodies 1 is turned upward or downward it prevents the free movement of the corresponding rib 16. In order to liberate the path for the ribs 16 the handles of the unsymmetrical locking bodies 1' (Fig. 6) must be lifted or lowered to bring their notches 3' 80 into the vertical position, according to whether said notch 3' at the inserting of the locking bodies has been placed above or below the longitudinal line of the corresponding rib 16.

In the form of construction shown four unsymmetrical locking bodies 1' are provided, which are however all of the same shape. Two such unsymmetrical locking bodies 1' are located in the upper row as central locking bodies and so that their handles have to be turned upward to bring the notches 3' onto the path of rib 16. Two locking bodies 1' are inserted in the lower row as central locking bodies and so that their handles have to be turned down to bring their notches 3' onto the path of the rib 16. To shift the spring bolt 15 for unlocking the lock, the two central locking bodies 1' in the upper row and the two extreme locking bodies 1 in the lower row have to remain in the central position, while in the upper row the handles of the two extreme locking bodies 1' have been turned upward and in the lower row the handles of the two central locking bodies 1' have been turned down. Normally, the lock being locked, all locking bodies are preferably in the central position, the four locking bodies 1' locking said spring-bolt. Any other adjusting may be selected, as for instance some locking bodies 1' may remain in the adjusted position and only one or two or any other number of locking bodies will have to be adjusted. 100 When the comb shaped retaining plate 10, which covers the journals of the locking bodies, is pulled out, any locking body may be removed and interchanged against another locking body, so that the grouping may be altered as desired. The comb shaped retaining plate 10 is secured in its covering position by a latch rod 22 fixed on a portion of the spring bolt, said rod having a latch nose 23 105 which engages with the notch 24 of the plate 110 115 120 125 130

10. Only when the spring-bolt is in the open position, is the nose 23 disposed to release the plate 10, and on the other hand the plate 10 can be inserted only when all locking bodies 5 are in the open position, as only then the spring bolt can be shifted into the open position. When the latch has not been brought into the open position, the nose 23 of rod 22, which is connected to the latch, is lying 10 under the slot 9 of the casing and locks the same, so that the comb shaped retaining plate 10 cannot be inserted into the slot. If one holds the latch in the open position, the nose 23 of rod 22 is at the side of the slot 9 of the 15 casing and the comb shaped retaining plate can be removed or inserted. The owner of the lock, after the re-grouping of the locking bodies, cannot make the lock ready for use without seeing which position the locking 20 bodies must assume for opening the lock.

The construction of the spring bolt may be different according to the utilization of the lock. For portfolios and trunks the locking bolt can be constructed as shown in the drawings. It carries a knob 5, the shaft of which traverses a slot 26 of the casing. On the cover-plate of the casing a spring latch 27 is shiftably mounted by means of slots 28 therein engaging retaining and guide studs 30 or pins on said cover plate, and this latch has a longitudinal slot 29 through which the shank of the shifting knob 25 projects. In the casing a slit 30 is further arranged through which a barbed hook 31 on the lid 35 of the portfolio or of the trunk can penetrate into the lock. The latch has under the slot 30 an aperture 32 and a tongue 33, extending into the range of slot 30. A spring 34 acts on the latch 27 and pushes the tongue 40 33 of the same into the range of slot 30. When the barbed hook 31, which is rounded, is pressed into slot 30, it pushes to the side the tongue 33 and by the same the latch 27 which, moving in its bearing slots 28 and 29, is 45 pushed back by the action of spring 34 to engage over hook 31. As the spring-bolt 15 has not to be shifted in this case, it is not necessary to adjust the locking bodies to the correct open position. The lock can 50 therefore be locked at any adjusting of the locking bodies, but for unlocking the lock all the locking bodies have to be brought into the correct position before the spring bolt 55 15 can be pushed back by the shifting knob 25 the latter moving also the latch 27 so that it releases the barbed hook 31. On the drawing the spring bolt is shown pushed back into the open position, in opposition to the action of spring 34.

60 I claim:—

1. In a permutation lock the combination of a bearing body with a number of disc-shaped locking elements, each locking element having a short axle projecting at both ends from the disc, the bearing body having

slots in transverse direction and longitudinal grooves intersecting said transverse slots the locking elements inserted with their discs in said transverse slots and oscillatably mounted with their axles in said longitudinal grooves, a device for holding said locking bodies in the bearing body, and a transverse spring bolt, shiftable with regard to said disc and adapted to be locked by said discs. 70

2. In a permutation lock the combination of a bearing body with a number of disc-shaped locking elements, each locking element having a short axle projecting at both ends from the disc, the bearing body having rows of slots in transverse direction and longitudinal grooves intersecting said transverse slots the locking elements inserted with their discs in said transverse slots and oscillatably mounted with their axles in said longitudinal grooves, a device for holding said locking bodies in the bearing body, and a spring bolt with ribs transversely directed and shiftable with regard to the discs of the locking elements, intersecting and penetrating through the same and having notches in the rims, said ribs having also notches, the locking elements fitting with their discs into said notches of the ribs and locking said ribs against shifting when not correctly adjusted. 80 90

3. A permutation lock comprising a number of disk-shaped locking bodies having each a notch and a handle and a short axle, a bearing body, having transverse slots and semicircular longitudinal grooves, said locking bodies being adapted to be inserted with their disk-shaped part into said transverse slots and with their axles into said longitudinal grooves of said bearing body and to be oscillated in the same, the disk-shaped part of said locking bodies projecting laterally from the transverse slot of said bearing body, a number of springs, each spring acting upon the projecting disk-shaped part of one locking body, said disk-shaped part of each locking body having an indentation in each side, beads on the ends of said springs engaging with said lateral indentations of said locking bodies to secure said locking bodies in their adjusted position, a device for holding said locking bodies in their bearings, and a spring-bolt with ribs each rib corresponding to the notches of one row of locking bodies, said ribs having notches into which said locking bodies fit. 100 105 110 115

4. A permutation lock comprising a number of disk-shaped locking bodies having each a notch and a handle and a short axle, a bearing body having transverse slots and semicircular longitudinal grooves said locking bodies being adapted to be inserted into said bearing body and to be oscillated in the same, a casing having a slot in one side-wall above said bearing body, a comb shaped retainer inserted through this slot and engaging with its teeth between said locking bodies 120 125 130

for holding the same in their bearings, means for locking said comb shaped retainer, when the lock is in the closed position, and a spring bolt having ribs intersecting the disk-shaped parts of said locking bodies substantially as described.

5. A permutation lock, comprising in combination a number of disk-shaped locking bodies, a bearing body, said locking bodies adapted to be inserted into said bearing body and to be oscillated in the same, a casing having a slot in one side-wall beneath which the said bearing body is fixed, a comb shaped retainer adapted to be inserted into said slot 10 of said casing and engaging with its teeth between said locking bodies to securely hold the same in their bearings, means for locking said comb shaped retainer when the lock is in the locking position, a spring bolt, ribs on 15 said spring-bolt intersecting the disk-shaped parts of the locking bodies, said spring bolt being mounted on said bearing body and in said casing shiftably mounted on said casing and on said spring bolt, a push knob on said spring-bolt projecting from said casing, said casing having a slot therein, and a barbed hook adapted to 20 be inserted into said slot and engaged by said latch, substantially as described.

6. A permutation lock, comprising in combination a number of disk-shaped locking bodies, a bearing body, said locking bodies adapted to be inserted in rows into said bearing body and to be oscillated in the same, a casing having a slot in one side-wall, a bearing body fixed in said casing underneath said slot in the side-wall of the casing, a comb shaped retainer adapted to be inserted into said slot of said casing and engaging with its teeth between said locking bodies to 25 securely hold the same in their bearings, a spring bolt, ribs on said spring bolt intersecting the disk-shaped parts of the locking bodies, said spring bolt being mounted on said bearing body and in said casing, said locking bodies and said ribs of said spring bolt being in engagement so that only at correct adjusting of the locking bodies shifting of said spring bolt is possible, a spring-controlled latch on said spring bolt, a rod 30 on a part of said spring-bolt, and a locking nose at the end of said rod, the comb shaped retainer having a notch and said locking nose of said rod engaging with said notch when said spring bolt is locked and said retainer is 35 inserted in the slot in the casing.

7. In a permutation lock, a lock casing provided with open bearings, a plurality of disk-shaped locking members independently and removably journaled in said bearings for oscillating movement, each member having a

radial slot and an adjusting handle arranged in a predetermined position with respect to said slot, a retaining device common to all of said locking members for holding the disks journaled in the open bearings and movable to a position to permit removal of any locking member from its bearing and the insertion of another locking member in its place, and a locking element having alternating projections and recesses to respectively engage the radial slots in the locking members to hold said members from oscillation and to receive the body portions of said members and permit oscillation thereof.

8. In a permutation lock, a lock casing provided with open bearings, a plurality of disk-shaped locking members independently and removably journaled in said bearings for oscillating movement, each member having a radial slot and an adjusting handle arranged in a predetermined position with respect to said slot, a movable comb-shaped retainer plate common to all of said locking members for holding the locking members journaled in the open bearings and movable to a position to permit removal of any locking member from its bearing and the insertion of another locking member in its place, and a locking element having alternating projections and recesses to respectively engage the radial slots in the locking members to hold said members from oscillation and to receive the body portions of said members and permit oscillation thereof.

9. In a permutation lock, a lock casing provided with open bearings, a plurality of disk-shaped locking members independently and removably journaled in said bearings for oscillating movement, each member having a radial slot and an adjusting handle arranged in a predetermined position with respect to said slot, a retaining device common to all of said locking members for holding the disks journaled in the open bearings and movable to a position to permit removal of any locking member from its bearing and the insertion of another locking member in its place, a locking element having alternating projections and recesses to respectively engage the radial slots in the locking members to hold said members from oscillation and to receive the body portions of said members and permit oscillation thereof, and locking and releasing means for said retaining device operable by and movable with the locking element to lock said device against movement when the ribs of the locking element are engaged with the slots of the disk-shaped locking members and to release said device when the recesses of the locking element 110 align with the bodies of said members.

10. In a permutation lock, a lock casing provided with open bearings, a plurality of disk-shaped locking members independently and removably journaled in said bearings for

- oscillating movement, each member having a radial slot and an adjusting handle arranged in a predetermined position with respect to said slot, a sliding comb-shaped retaining plate common to all of said locking members for holding the locking members journaled in the open bearings and movable to a position to permit removal of any locking member from its bearing and the insertion of another locking member in its place, a locking element having alternating projections and recesses to respectively engage the radial slots in the locking members to hold said members from oscillation and to receive the body portions of said members and permit oscillation thereof, and means for locking the comb shaped retaining plate from movement when the ribs of the locking element are engaged with the slots of the locking bodies and releasing said plate from movement when the recesses of the locking element are alined with the bodies of the locking members. 75
11. In a permutation lock, a lock case, a plurality of disk-shaped locking bodies each having a radial notch and a handle of a predetermined relation with respect to each other, said bodies being oscillatably journaled in the lock case for independent insertion and removal, a lock bolt having projections to engage the notches in the locking bodies when alined to permit sliding movement of the bolt and prevent oscillating movement of any of the locking bodies when the bolt is thrown and having recesses to receive the locking bodies and permit oscillation thereof when the bolt is retracted, a retainer movable to different positions to hold the locking bodies from removal and to release them and permit of their removal, and means governed by the bolt to normally lock the retainer in holding position until the bolt is retracted and release it for releasing movement when the bolt is retracted. 80
12. In a permutation lock, a lock case having open bearings, a plurality of disk-shaped locking members each having a notch and a handle of a restricted fixed relationship, the notches in some of the locking bodies being symmetrical to and the notches in others of the locking bodies being unsymmetrical with regard to the handles of said bodies, said bodies being journaled for oscillation and independent insertion and removal in said open bearings, and a lock bolt having ribs corresponding to the notches in the locking bodies and recesses alternating with the ribs spaced to correspond to the spacing of the bodies. 85
13. In a permutation lock, a lock case, two parallel rows of disk-shaped locking bodies, each having a notch and a handle, the lock case being provided with open bearings in which said bodies are journaled for oscillation and independent insertion and removal, a device for holding said bodies in their bear- 90
- ings and movable to a position to release and permit of the removal of any body from its bearing, and a lock bolt having rows of spaced ribs and recesses for coaction with the rows of locking bodies. 95
